(57) **CLAIM**

The ornamental design for an eyewear for augmented perception, as shown and described.

DESCRIPTION

FIG. 1 is a top perspective view of eyewear for augmented perception, showing my new design;

FIG. 2 is a rear perspective view thereof;

FIG. 3 is a front view thereof;

FIG. 4 is a rear view thereof;

FIG. 5 is a right-side view thereof;

FIG. 6 left-side view thereof

FIG. 7 is a top view thereof; and,

FIG. 8 is a bottom view thereof.

The broken lines in the drawings illustrate portions of the eyewear for augmented perception and form no part of the claimed design.
